Primary Examiner — Cynthia Ramirez(74) *Attorney, Agent, or Firm* — Patterson & Sheridan, L.L.P.(57) **CLAIM**

The ornamental design for a cart, as shown and described.

DESCRIPTION

FIG. 1 is a top front perspective view of a cart in a first position showing my new design;

FIG. 2 is a top rear perspective view thereof;

FIG. 3 is a bottom front perspective view thereof;

FIG. 4 is bottom rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top plan view thereof;

FIG. 10 is a bottom plan view thereof;

FIG. 11 is a top front perspective view of the cart in a second position;

FIG. 12 is a top rear perspective view thereof;

FIG. 13 is a bottom front perspective view thereof;

FIG. 14 is bottom rear perspective view thereof;

FIG. 15 is a front elevational view thereof;

FIG. 16 is a right side elevational view thereof;

FIG. 17 is a rear elevational view thereof;

FIG. 18 is a left side elevational view thereof;

FIG. 19 is a top plan view thereof; and,

FIG. 20 is a bottom plan view thereof.

The broken lines shown in the figures are included for the purpose of illustrating environment and forms no part of the claimed design.
